CLAIM

The ornamental design for a microwave container with cover, as shown and described.

DESCRIPTION

FIG. 1 is a top, side and front perspective view of a microwave container with cover showing my new design;
 FIG. 2 is a front elevation view thereof;
 FIG. 3 is a rear elevation view thereof;
 FIG. 4 is a right side elevation view, the left side elevation being a mirror image thereof;
 FIG. 5 is a top plan view thereof;
 FIG. 6 is a bottom plan view thereof;
 FIG. 7 is a bottom, side and rear perspective view thereof; and,
 FIG. 8 is an exploded perspective view thereof, shown with the cover removed for completeness of illustration.
